Primary Examiner — George A Bugg*Assistant Examiner* — Jessica A Jenkins(74) *Attorney, Agent, or Firm* — CIONCA IP Law P.C.(57) **CLAIM**

The ornamental design for a duffel bag as shown and described.

DESCRIPTION

FIG. 1 is a front left perspective view of a duffel bag showing the new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is another front elevation view showing decorative patches.

The broken lines of the drawing depict non-claimed portions of the duffel bag and form no part of the claimed design.

1 Claim, 8 Drawing Sheets(56)
